2,611,384

STEAM LOCOMOTIVE INJECTOR
ATTACHMENT

William F. Smith, Sr., Minneapolis, Minn.

Application September 25, 1950, Serial No. 186,551

6 Claims. (Cl. 137—202)

1

This invention relates to locomotive injector attachments and the principal objects are to provide apparatus for economizing feed water and for the elimination of hazards during freezing weather which usually exist when the overflow of the injectors, now in common use, is discharged alongside the railroad tracks.

It has been proposed, in the past, to conserve water introduced through the injector for priming purposes, by providing a steam jet to return such water to the water supply tank from the overflow conduit of the injector. An example of such is shown in the patent to Heath, 1,145,683 of July 6, 1915. This arrangement has been found unsatisfactory in that it uses some of the steam of the boiler for the return of water to the supply tank, and since the jet is likely to become clogged it is necessary to run an ordinary overflow conduit for discharge along the railroad track in the event that the jet becomes clogged. This ordinary overflow conduit, having its way in communication with the injector and the zone of the jet, is apt to deliver dust, dirt or other foreign matter into the water and parts of the jet, when the jet is operating under normal conditions to return the priming water to the water supply tank. This foreign matter is likely to clog the jet or find its way to the water supply tank and subsequently be introduced into the injector or boiler after passing through the injector.

It has also been proposed to economize as to feed water, dispensing with the jet above referred to and in its place substitute a receiving tank connected to the injector overflow, the lower portion of the receiving tank having in communication therewith a return pipe with one or more liquid seals or traps, the return pipe being connected with the usual water supply pipe of the injector adjacent the latter. An example of such is shown in patent to Shields 1,902,732 of March 21, 1933. This has been found unsatisfactory in that the receiving tank must be vented to the atmosphere so that the water therein will flow by gravity through the liquid seal or trap to the injector water supply pipe when the injector is shut off. However, when the injector is set into operation some steam will issue from the vent into the engine cab and create an annoyance if not a hazard to the engineer and those workmen in the cab. Furthermore the liquid seals or traps take up considerable space in the engine cab, which is objectionable because of other standard equipment in the cab.

According to my invention, water from the overflow of the injector is collected in an over-

2

flow receptacle or box during operation of the injector and returned to the tender supply tank instead of being distributed alongside the railroad tracks where it is likely to form ice, during freezing weather, and create a hazard to workmen, such as switchmen and brakemen, who must walk along and perform operations adjacent to the tracks and rolling stock. The steam issuing from the injector to the atmosphere is also conducted from the overflow box and vented at a zone above the locomotive cab, until the overflow box is substantially filled with water, whereupon a float valve closes off venting of the steam. Upon stopping operation of the injector, the water in the overflow box descends, due to the force of gravity, consequently causing the float valve to descend and the water finally is conducted back to the tender water supply tank.

Another object of the invention is to provide means for introducing the feed water, collected from the overflow of the inspirator, into the water supply tank of the locomotive tender through flexible hose of the type dropped between the tender and locomotive, for supply of water to the inspirator, and to heat the retrieved water in such hose during freezing weather.

Other objects and advantages will appear in the following detailed description of a highly satisfactory embodiment of my invention, taken in connection with the accompanying drawings, forming a part of this specification, and in which drawings:

Fig. 1 is a view in side elevation somewhat diagrammatically illustrating a locomotive, a portion of its tender, a typical injector installation, and an attachment, according to the present invention, associated with parts of the injector, locomotive and tender.

Fig. 2 is a detail view partly in elevation and partly in vertical section, showing the injector and the attachment according to the present invention connected thereto, and showing the water supply tank of the tender and connections therewith on a smaller scale.

Fig. 3 is an enlarged sectional view on the line 3—3 of Fig. 1, showing the overflow box in plan.

Fig. 4 is a detailed plan view of the overflow box, with its cover removed.

Fig. 5 is a horizontal sectional view on the line 5—5 of Fig. 2.

Fig. 6 is an enlarged detailed view partly in elevation and partly in vertical section showing the float valve, forming a part of my invention, in a seated position.

In the drawings are shown a typical locomotive

6, in the cab 7 of which is located an injector 8, including an overflow outlet 9, and a steam turret 10; a tender 11 containing a water supply tank 12, detachably connected to the locomotive as by any suitable coupler 14; a feed water supply line 15 between the tank 12 and injector 8; a steam pipe 16 between the turret 10 and injector 8; and apparatus 17 constructed and arranged according to the present invention and associated with the injector 8, water supply tank 12 and turret 10.

The injector may be of any suitable type, that shown being the well known Hancock injector or inspirator, including a water control valve 19, steam control valve mechanism 20 and feed water delivery pipe 21. The water supply line 15 may comprise a rigid pipe section 22, carried by the locomotive, a flexible section or hose 23 secured to the rear end of section 22 by a detachable coupling 24; and a goose neck section 25 carried by the tender and disposed mainly in the water tank 12 thereof, as shown in Fig. 2, the rear end of the hose 23 being secured to the lowermost end of the goose neck section by a detachable coupling 26 in the usual manner. The goose neck section is shown provided with the usual vent valve 27 for the escape of air as the tank is being filled and to prevent the siphoning of water from the tank when the hose section is disconnected from either section 22 or section 25. The maximum water level in the supply tank is indicated by the line 29, Fig. 2, and the injector is installed in the locomotive cab sufficiently high above the plane of the water level in the tank 12 to permit parts of the apparatus 17, as hereinafter described, to also be located above said plane.

The apparatus 17 preferably comprises a receiving tank 30 located below the injector 8 with the bottom of its chamber 31 preferably at about the maximum water level 29 in the tender tank 12, as shown in Fig. 2; a vent pipe 32 connected to the receiving tank at the upper portion thereof for venting the chamber to the atmosphere; a conduit connection 33, preferably including a union 34, between the overflow outlet 9 of the injector 8 and the upper portion of the receiving tank 30 whereby steam and water issuing from the injector during the primary stage of operation will find its way into the chamber 31; a float valve mechanism 36 in the tank 30 for shutting off communication between the chamber 31 and the vent pipe 32 when the receiving tank is substantially filled with water; a water return line 38 operatively connected with the receiving tank 30 and tender tank 12, independent of the water suction supply line 15, for return of water from the receiving tank to the tender tank; and a baffle plate 40 located in the chamber 31 between the zone of the inlet of conduit connection 33 thereto and the zone of the outlet of the chamber 31 to the water return line 38, as shown in Fig. 2.

The receiving tank 30 is preferably horizontally elongated in shape and may have its one end wall 41 inclined downwardly from its top wall 42 to its bottom wall 43, and the other end wall 44 may be vertical. The top wall 42 may be detachably connected to the main body portion of the tank by means of stud bolts 45. The receiving tank may be supported by a bracket 46 detachably connected with some part of the locomotive in any suitable manner.

The vent pipe 32 preferably comprises a lower section 47 connected to the upper portion of top wall 42 at a threaded boss 48, adjacent the end wall 44, and an upper section 49 which prefer-

ably extends through the roof 50 of the locomotive cab 7 so that its outlet is located exteriorly of the locomotive and hence steam issuing therefrom will not disturb or annoy workmen in the locomotive cab. A union 51 may be provided, connecting the sections 47 and 49.

The conduit connection 33 is preferably located adjacent the wall 41, and the unions 34 and 51 facilitate detachment of the receiving tank 30 with respect to the injector 8 and the vent section 49.

Referring now to the flow valve mechanism in the example shown, it comprises a float valve proper 53, such as a ball valve adapted to engage 15 a downwardly facing valve seat 54 which may be machined or otherwise formed at the lower end of the lower section 47 of the vent pipe and threaded boss 48, as shown in Fig. 6, and a cage 55 for vertically guiding the valve proper 53, during 20 its movement from a lower position, when the chamber 31 is empty of water to an upper closing position with respect to seat 54, when the chamber 31 is substantially filled with water. The cage 55 may be detachably secured in place, as 25 by stud bolts 56 connecting it with the top wall 42, and if desired, by stud bolts 57 connecting it with the bottom wall 43.

The water return line 38 may comprise a rigid conduit or pipe section 60, a flexible conduit 61, 30 a shut off valve 62 beneath the water tank 12 of the tender, a nipple 63 secured to and communicating with the tank 12, and unions 64, 65 and 66 to facilitate detachment of parts, the union 64 connecting the rear end of flexible conduit 61 with valve 62, the union 65 connecting the forward end of flexible conduit 61 with the rear end of rigid conduit 60; and the union 66 connecting the forward end of rigid section 60 with a nipple 68, formed on the bottom wall 43 40 of receiving tank 30. The flexible conduit 61 is drooped in the usual manner, similar to flexible section or hose 23 of the feed water supply line 15, permitting relative movement between the locomotive and tender, such as when travelling over curved track.

The baffle plate 40 may be secured in the chamber 31 in any suitable manner, such as by stud bolts 70, and is preferably provided with a plurality of perforations 71 so as to not require all 50 of the water entering through the conduit connection 33 to pass around the baffle plate.

In order to prevent freezing of water in the water return line 38, I provide a valve controlled conduit 72 in communication with the steam space of the locomotive boiler, such as by connection at the steam turret 10, this conduit preferably extending through the receiving tank 30 and along the interior of at least the rigid conduit or pipe section 60 of the water return line 35. In the example shown, the conduit 72 has its outlet 73 adjacent the union 65, so that steam issuing therefrom will heat the water in the flexible conduit or hose 61. The valve 74 in the heating conduit 72 may be located adjacent the receiving tank 30, convenient to the engineer having charge of operation of the injector.

In operation, when it is desired to introduce water into the locomotive boiler, the steam control valve mechanism 20 of the injector 8 is operated by the attendant in the usual manner, first for priming, and then for water delivery operation. During the priming operation, steam entering the chamber 31 strikes the baffle plate 40 in a manner so as to not impart a voluntary movement for the float valve proper 53 and the

steam finds exit to the atmosphere through the vent pipe 32, preferably above the roof of the locomotive cab. During the priming operation of the injector, water is finally introduced into the chamber 31, and as it rises therein, the float valve proper 53 will be carried upwardly in its cage 55 and will finally engage seat 54 shutting off escape of fluid through the vent pipe 32. When this takes place water in the return line 38 will be forced into the water supply tank 12 by any superatmospheric pressure in chamber 31 and when the priming of the injector has been completed, and the steam control valve mechanism 20 of the injector has been set for introduction of water into the locomotive boiler, any superatmospheric pressure in the chamber 31 will be dissipated and when there is only atmospheric pressure in the chamber 31, the float valve 53 will become unseated, and the water in the receiving tank 30 will flow by gravity to the water return line 38 and finally back into the water supply tank 12, as a result of subsequent operations of the injector.

In practice I have found that the receiving tank may be relatively small such as to provide a chamber 31 approximately four inches wide, eight inches deep and twelve inches long. When installed, it may be disposed closely adjacent to and below the injector, with its longitudinal axis diagonally with respect to the axis of water delivery pipe 21 so that its rear end will be centered beneath the overflow outlet 9 of the injector and so that the pipe section 49, of the vent pipe 32 will clear the water delivery pipe 21 at either side of the latter.

I claim:

1. In a water supply system for steam locomotives of the type in which an injector, having a water suction supply line connection with a tender tank, and a steam supply line and a water delivery line connected with the locomotive boiler, is provided with an overflow outlet through which steam and water escapes during priming of the injector; the improvement which comprises a receiving tank connected with the overflow outlet below the injector, a vent pipe connected to the receiving tank at the upper portion thereof, a float valve mechanism in the receiving tank for shutting off communication between the interior of the receiving tank and the vent pipe when the receiving tank is substantially filled with water, and a water return line operatively connected with the receiving tank and tender tank independent of said water suction supply line for return of water from the receiving tank to the tender tank.

2. In a water supply system for steam locomotives of the type in which an injector, having a water suction supply line connection with a tender tank, and a steam supply line and a water delivery line connected with the locomotive boiler, is provided with an overflow outlet through which steam and water escapes during priming of the injector; the improvement which comprises a receiving tank connected with the overflow outlet below the injector, a vent pipe connected to the receiving tank at the upper portion thereof and having its outlet located exteriorly of the locomotive, a float valve mechanism in the receiving tank for shutting off communication between the interior of the receiving tank and the vent pipe when the receiving tank is substantially filled with water, and a water return line operatively connected with the receiving tank and tender tank independent of

said water suction supply line for return of water from the receiving tank to the tender tank.

3. In a water supply system for steam locomotives of the type in which an injector, having a water suction supply line connection with a tender tank, and a steam supply line and a water delivery line connected with the locomotive boiler, is provided with an overflow outlet through which steam and water escapes during priming of the injector; the improvement which comprises a receiving tank connected with the overflow outlet below the injector, a vent pipe connected to the receiving tank at the upper portion thereof and having its outlet located exteriorly of the locomotive above its cab, a float valve mechanism in the receiving tank for shutting off communication between the interior of the receiving tank and the vent pipe when the receiving tank is substantially filled with water, and a water return line operatively connected with the receiving tank and tender tank independent of said water suction supply line for return of water from the receiving tank to the tender tank.

4. In a water supply system for steam locomotives of the type in which an injector, having a water suction supply line connection with a tender tank, and a steam supply line and a water delivery line connected with the locomotive boiler, is provided with an overflow outlet through which steam and water escapes during priming of the injector; the improvement which comprises a horizontally elongated receiving tank located below the injector and having a connection with said overflow outlet thereof for receiving steam and water into its chamber at the upper portion of one end thereof, a vent pipe connected to the receiving tank and having communication with its chamber at the other upper end thereof, a float valve mechanism in the receiving tank for shutting off communication between the chamber thereof and the vent pipe when said chamber is substantially full of water, and a water return line operatively connected with the lower portion of said receiving tank and tender tank.

5. In a water supply system for steam locomotives of the type in which an injector, having a water suction supply line connection with a tender tank, and a steam supply line and a water delivery line connected with the locomotive boiler, is provided with an overflow outlet through which steam and water escapes during priming of the injector; the improvement which comprises a horizontally elongated receiving tank located below the injector and having a connection with said overflow outlet thereof for receiving steam and water into its chamber at the upper portion of one end thereof, a vent pipe connected to the receiving tank and having communication with its chamber at the other upper end thereof, a float valve mechanism in the receiving tank for shutting off communication between the chamber thereof and the vent pipe when said chamber is substantially full of water, and a water return line operatively connected with the lower portion of said receiving tank and tender tank, and a baffle plate located between the zone of the steam and water inlet and the water return outlet of the receiving tank.

6. In a water supply system for steam locomotives of the type in which an injector, having a water suction supply line connection with a tender tank, and a steam supply line and a water delivery line connected with the locomotive boiler, is provided with an overflow outlet through

which steam and water escapes during priming of the injector; the improvement which comprises a receiving tank connected with the overflow outlet below the injector; a vent pipe connected to the receiving tank at the upper portion thereof, a float valve mechanism in the receiving tank for shutting off communication between the interior of the receiving tank and the vent pipe when the receiving tank is substantially filled with water, a water return line operatively connected with the receiving tank and tender tank independent of said water suction supply line for return of water from the receiving tank to the tender tank, and a valve controlled conduit in communication with the steam space of the locomotive boiler and extending through said receiving tank and at least partially

along the interior of said water return line for supplying heat to the latter during freezing weather.
